UNITED STATES PATENT OFFICE.

JULIUS MOHS, OF DESSAU, GERMANY, ASSIGNOR TO DEUTSCHE WERKE AKTIEN-
GESELLSCHAFT, OF BERLIN, GERMANY, A CORPORATION OF GERMANY.

GRATER.

1,408,762.

Specification of Letters Patent.

Patented Mar. 7, 1922.

Application filed October 22, 1921. Serial No. 509,753.

To all whom it may concern:

Be it known that I, JULIUS MOHS, a citizen of Germany, residing at Dessau, Germany, have invented new and useful Im-
5 provements in Graters, (for which I have filed application in Germany, K 68283 X/34b, dated 3 Mar., 1919, and M. 67614 X/34b, dated 6 Dec., 1919,) of which the following is a specification.

10 This invention relates to rotary graters operated by a crank handle and which ordinarily are provided with a stationary grating for scraping away the material from the rotary grater-disk. These stationary grat-
15 ings are rigid and unable to adapt themselves closely against the surface of the rotary grater-disk because these latter are usually made of sheet metal and do not turn true in all respects so that the grating can-
20 not uniformly make contact with the rotary disk. Under these conditions it is impos-
sible to obtain uniformly grated material by the aforesaid graters.

The object of this invention is to provide
25 a springy grating connected with a rigid stationary carrier for same to enable said grating to come evenly into contact with the convex surface of the grater-disk and to be so retained during the working of the ap-
30 paratus that the material shall be uniformly scraped off the grater-disk.

The adoption of a stationary carrier forming a rigid backing to the springy grating permits the latter to have its upper surface-
35 portion fitted close against the grater-disk, said grating being in close proximity of the stationary backing and unable to yield even under exceptional pressure.

In experimenting, it has been established
40 that the thinner the elastic grating plate is made, the more evenly will it press against the convex grater-disk and the more readily will the grating substances be cut in cross-
45 wise direction at their contact with the grating. For this purpose it is important that the thin elastic grating plate shall have a backing extending around the whole con-
tour of same so as to prevent the thin grating from yielding at its lower portion or at

any other part, for the perfect working or 50 cutting action between the grater-disk and the grating would not be attained and an imperfectly grated material would leave the apparatus.

To ensure for a uniformly fine and regular 55 pasty material from the grating apparatus, the present invention provides a stationary grating carrier with curved ribs or arms against which the thin elastic grating plate rests and is thus able to conform more easily 60 to the curvature and inaccuracy of the grater disk, so that the long continuous strings of grated material from the rotary disk are transversely cut in the grating to form a fine pasty mass. 65

An embodiment of the invention is shown in the accompanying drawings, in which:

Figure 1 is a front elevation; Fig. 2 is a vertical transverse section of the apparatus.

The usual grater disk *a* is rotatably 70 mounted in the casing *b* by means of the shaft *c* and can be rotated by a crank handle in the usual manner. *e* is the elastic grating which has an angular portion *d* by which it is held in a slit in the carrier *g* in such a 75 manner as to prevent sidewise tilting.

The carrier *g* has a backing which keeps the grating applied against the rear face of the grater-disk *a* and enables said grating to make elastic contact with the disk which latter is pressed towards the grating by the substance being reduced. The pressure of the substance under treatment is exerted by a swinging arm *h* pivotally mounted in the casing *b*. The arm *h* is operated by a toothed segment *n* fast on the pivot thereof, said segment meshing with a segment *o* connected with a hand lever *i*. 80

To obtain an almost perfect pasty mate-
rial, the stationary carrier and backing *g* 90 are provided with curved ribs *m* against which the thin elastic grating bears whilst yielding to the curvature of the grater-disk, and in this manner is enabled to more read-
ily cut the strings of material coming from 95 the grater-disk, into minute particles to form a fine pasty mass.

According to this invention, the thin elas-

tic grating *e* is secured to the lower rib *m* of the carrier *g* by a hinge-joint *q*, while its upper end is retained by the aforementioned angle portion *d* seated in the slit of the carrier *g*.

The hinge-joint enables the grating *e* to be detached for cleaning and other purposes, while at the same time the ribs *m* can be cleaned.

10 It may be mentioned that the ribs *m*, forming backing for the grating *e*, may have any desired form or configuration and that the openings in the grating *e* may have various shapes and dimensions.

15 I claim:

1. A grating apparatus comprising a casting, a rotary grater-disk mounted against the open front thereof, an elastic grating in

contact with said disk and a carrier for said grating.

2. A grating apparatus comprising a casting, a rotary grater-disk mounted against the open front thereof, an elastic grating in contact with said disk, a carrier for said grating, and ribs depending from said carrier and forming a backing for said grating.

3. A grating apparatus comprising a casting, a rotary grater-disk mounted against the open front thereof, an elastic grating in contact with said disk, a carrier having depending ribs to form a backing for said grating and a hinge-joint connecting said grating with the carrier.

JULIUS MOHS.
